(57) **CLAIM**

The ornamental design for a picture frame, substantially as shown.

DESCRIPTION

The novel design of picture frame consisting of a heart shaped frame with a musical staff marketed under the name LOVE NOTES, is intended to include a recording device that enables the purchaser to record a short message that can be played back by the recipient.

FIG. 1 is a perspective view of the picture frame of the present invention;

FIG. 2 is a top view of the present invention;

FIG. 3 is a front view of the present invention;

FIG. 4 is a bottom view of the present invention;

FIG. 5 is a view of the right side of the present invention;

FIG. 6 is a rear view of the present invention; and,

FIG. 7 is a view of the left side of the present invention.
